UNITED STATES PATENT OFFICE.

CHARLES DEITSCH AND EDWARD J. DEITSCH, OF NEW YORK, N. Y.

DESIGN FOR A TOILET-SATCHEL OR BICYCLE-BAG.

SPECIFICATION forming part of Design No. 28,114, dated January 4, 1898.

Application filed July 22, 1896. Serial No. 600,169. Term of patent 7 years.

To all whom it may concern:

Be it known that we, CHARLES DEITSCH and EDWARD J. DEITSCH, citizens of the United States, residing at New York, in the county of New York and State of New York, have invented and produced a new and original Design for Ladies' Toilet Satchel or Bag for Bicycles; and we do hereby declare the following to be a full, clear, and exact description of the invention, such as will enable others skilled in the art to which it appertains to make and use the same.

In the drawings accompanying this specification and forming part thereof, Figure 1 is a rear view of the satchel or bag. Fig. 2 is a perspective view of the satchel or bag, and Fig. 3 is a sectional view.

Similar characters of reference designate like parts throughout the several views.

The leading features of our design consist of a satchel or bag having a rectangular sloping top or lid, the four walls expanding from the four edges of the said top and passing outward and downward on curved surfaces to the bottom, the front wall and rear wall being in substantially parallel planes and the bottom being convex and sloping upwardly at both edges thereof to meet and join the lower extremities of the front and rear walls.

Referring to the accompanying drawings,

the reference-character A designates the top or lid of the satchel or bag herein shown and described, which is rectangular in shape and slopes or inclines forwardly and downwardly, and the ends B of the satchel or bag expand outwardly and downwardly to the bottom C, where they attain their greatest width, and the bottom C is bulged outwardly or convex in shape and the side edges thereof extend upwardly above the central portion and join 35 the front and rear walls D and E, which are flared or extended laterally, and the edges thereof extend outwardly and downwardly from the top or lid A, and the corners are rounded or curved and the front and rear 40 walls D and E lie in substantially parallel 45 planes.

Having fully described our new and useful design in relation to the shape or configuration thereof, what we claim, and desire to secure by Letters Patent, is—

A design for toilet-satchels or bicycle-bags as herein shown and described.

In testimony whereof we affix our signatures in presence of two witnesses.

CHARLES DEITSCH.
EDWARD J. DEITSCH.
